UNITED STATES PATENT OFFICE.

BASIL G. AUSTIN, OF HARTFORD, CONNECTICUT, ASSIGNOR TO AUSTIN ORGAN COMPANY, OF HARTFORD, CONNECTICUT, A CORPORATION OF MAINE.

ELECTROPNEUMATIC ORGAN ACTION.

Application filed October 21, 1919. Serial No. 332,217.

To all whom it may concern:

Be it known that I, BASIL G. AUSTIN, a citizen of the United States, residing at Hartford, in the county of Hartford and 5 State of Connecticut, have invented certain new and useful Improvements in Electropneumatic Organ Actions, of which the following is a specification.

This invention relates to an electropneumatic organ action. I might make it clear at this point that I use this title more or less for convenience. While the structure in practice, has demonstrated marked utility in the art identified, it is conceivable that it 10 may with advantage be used in similar fields, such for instance, as in an automatic piano player. The construction involves in its make up what might be properly considered as an electropneumatic valve unit. This in 15 fact is really the primary object in view, namely, the provision of an article of the character set forth, which is simple in construction and effective in action, and which may be mounted and dismounted in fact as 20 a unit. The unit, in fact, involves a valve mechanism and a magnet mechanism. It is within the bounds of possibility that these mechanisms or sub-units might be individually used; that is to say, while desirably 25 the magnet mechanism is carried upon the valve mechanism, this may not be so in all cases, yet it is, as I have intimated, rather an important feature of the invention. The valve mechanism as I have considered it is 30 generally composed of several parts.

In the drawing accompanying and forming part of the present specification, I have shown in detail one of the several forms of embodiment of the invention which to enable those skilled in the art to practice the same will be set forth fully in the following description. I am not necessarily restricted to this disclosure. I may depart therefrom in several respects within the scope of the 45 invention defined by the claims following said description.

Referring to said drawings:

Figure 1 is a sectional view of an electropneumatic organ action involving the invention and showing certain parts by full and dotted lines.

Fig. 2 is a vertical section on the line 2-2 of Fig. 1 looking in the direction of the arrows.

Fig. 3 is a sectional elevation of the unit

and Fig. 4 is a practically similar view of the same and both illustrating slight modifications.

Fig. 5 is a face view of the casting of the valve mechanism.

Like characters refer to like parts throughout the several views which are on different scales.

The organ involves a pressure box or chamber as 2 mounted on the support 3, the latter in fact being enclosed by the pressure box or chamber and virtually forming a part or wall thereof. On the support 3 is mounted the bellows 4, to the movable member of which is connected the arm 5, the spring 6 being jointed to the outer end of the arm and also to the front of the pressure chamber or box. To the top of the pressure box or chamber is shown connected the boot of a pipe 7 fitted in a port 8 and adapted to be normally closed by the valve 9. The valve 9 is held against its seat at the lower end of the port by the power of the spring 6, as will be later explained. Supported at its elbow for rocking movement upon the top of the pressure box or chamber is the angle lever 10, the long arm of which is jointed to the arm 5 and to the short arm of which is connected the valve 9 shown as being closed by full lines in Fig. 1. It will be assumed that the bellows 4 is caused to collapse, for example to the dotted line position in Fig. 1. This draws the rod 5 to the left in said view and stretches the spring 6. As the rod thus moves to the left it swings the angle lever 10 to the dotted line position and as a consequence opens the valve 9 and admits pressure to the pipe 7 to cause the same to speak, by way of course of the port 8. The support 3 is furnished with an angular duct or passage 11, the upper end of which communicates with a port 12 in the back part of the bellows 4; this port 12 is common, being in communication with the interior of the bellows 4. Within the pressure box 2 is supported rigidly in some suitable manner and upon the support 3 a valve mechanism such as denoted in a general way by 14. This valve mechanism, as will be understood, involves some of the important features of the invention and comprises as shown two castings as 15 and 16 in all respects desirably duplicates of each other. I have found that each can be advantageously cast in a single piece. These sections

110

15 and 16 are practically of rectangular form having at what is considered the upper end, openings 17 and 18, the opening 17 being in register with the duct or passage 11 5 and constituting, therefore, a port, while the opening 18 is closed for instance by a disk 19 set into a rabbet therein as shown. The two sections 15 and 16 fit against each other and are secured in some suitable way 10 to the support 3, screws 20 being shown for the purpose.

The support 3 in addition to the passage or port 11, to which I have referred, has ports or ducts as 21 and 22, opening to the 15 atmosphere. As shown, the inner end of the port or passage 22 is in register with duplicate openings as 23 and 24 respectively formed in the lower ends of the sections 15 and 16. The two openings 23 and 24 mate 20 to constitute a port through the lower end of the valve mechanism 14.

The sections or castings 15 and 16 being in the present case duplicates of each other a description of one will apply to 25 the complementary part. This section 15, as is the case with the magnet mechanism, I have found by experiment can very advantageously be made by a metal die casting which I therefore prefer to employ. While 30 the parts 15 and 16 are interchangeable with each other, this of course is not so with the magnet mechanism, which is structurally different from the duplicate parts 15 and 16. The said casting or part 15 35 is virtually rectangular in shape. It has in it at the corners of a rectangle, four elongated ports 25, each surrounded on the inner side by a wall 26. In about the center, is a fifth port 27, practically of cruciform shape and surrounded by a wall 28, the several walls 26 and 28 being integral with the back or bottom of the part 15. The inner edges of these several walls 26 and 28 are in the same plane and presented a flat seat for a valve 29, having connected with its center the stem 30 of the valve 29, extending through the opening 27 of the part 16 rigidly connected in some suitable way with the movable member of 40 the bellows-like pneumatic 31. The base of said pneumatic is connected with a magnet mechanism such as that denoted in a general way by 32, and constituting a unitary part 45 of said magnet mechanism. The valve 29 is shown by full lines in Fig. 1 as occupying its seat against the part 15 and in dotted line against its seat on the part 16. It will, therefore, be clear that when the valve 29 is in its full line or normal position, pressure from the box 2 can be passed 50 through the ports of the part or casting 16 and from the interior of the unit 14 into the duct 11 and from the latter by way of the port 12, into the bellows 4, the consequence of this being that normally there

is pressure within and without the bellows 4 so that the spring 6 in the manner set forth can distend the bellows 4 as also shown by full lines in said view, and thus normally maintain the valve 29 closed in the 70 manner indicated. When, however, the pneumatic 31 is collapsed, as I will later explain, the valve 29 is drawn from its seat against the part 15 and onto its seat against the part 16 thus cutting off communication 75 between the bellows 4 and the interior of the pressure box or chamber 2 so that air will not pass in the manner to which I have just referred somewhat in detail. The valve 29 is shown by dotted lines as occupying 80 its shifted or abnormal position. When in this particular relation, it of course, as I have explained, cuts off communication between the interior of the bellows or pneumatic 4, and the interior of the pressure 85 box or chamber 2. When the valve is thus shifted, it of course, puts the bellows 4 into communication with the atmosphere by way of the port 12, duct 11, interior of the unit 14 and port 21, which latter opens directly to the atmosphere. In view of the latter circumstance the bellows or pneumatic 4 can be collapsed, and thus cause the air or pressure to pass from the box or chamber 2 to the pipe 7 in the manner already referred to.

I will hereinafter describe a way by which the valve 29 may be operated. To accurately guide this valve 29 I may provide a pin as 33, this pin being preferably 100 passed through perforations in the parts 15 and 16 and freely through a perforation in the valve 29, the three perforations obviously coinciding. The pin is also driven into the support 3. The stem 30, to which I 105 have somewhat briefly referred to, may be in the form of a screw passed through the central portion of the valve 29 and the threaded portion of which is in threaded engagement with the movable member of the 110 pneumatic 31; as shown, this screw 30 is surrounded by a sleeve 34 abutting at its ends against the inner side of the valve 29 and movable member of the pneumatic 31 respectively.

What I have referred to as the magnet mechanism 32 comprises the body portion 35 and the tube 36, connected with it, the tube depending from the body a short distance back of the central portion of said body. 120 The tube is of elbow or practically obtuse angular construction, its outer end being fitted flatwise against the part or casting 16 and being attached thereto in some convenient way. For instance, the free end of the 125 tube 36 may be furnished with lateral lugs 37 perforated to receive screws 20 in threaded connection with the lower end of the part or casting 16. The tube 36 constitutes a duct and is in direct communication with the 130

opening 24, which with the opening 23 constitutes a port through the valve unit, both of them being in communication with the port 22, which it will be recalled, opens directly to the atmosphere. The upper portion of the body 35 has an upstanding lug or projection 39 which fits flatwise against the stationary base of the pneumatic 31, the lug being perforated to receive the screw as 10 40 which is in threaded connection with said base. The body 35 in its upper portion, is closed by the plate 42. In the interior of the body 35 and rising from the bottom near the outer end thereof is a practically rectangular wall 43, the interior of which is in register with the inlet tube 36. This wall 43 presents a seat for the valve 44, shown as closed in Fig. 3. Fitted against the under side of the plate 42 is a packing strip 45 having an elongated slot 46 in constant communication with the interior of the chamber or box 2. When the valve 44 is closed, as shown in Fig. 3, pressure from the box 2 can enter the pneumatic 31 by way of the 25 ports 47 and slot 46.

The base board of the magnet mechanism 32 has a nipple 48 which fits an opening in the stationary member of the pneumatic 31, so that pressure may normally enter said 30 bellows to maintain the same distended and as a consequence also hold the valve 29 closed to prevent the communication of the bellows 4 with the atmosphere. The valve 44 is provided with an armature for the electromagnet 41 and when the electromagnet is energized, as I will later explain, it attracts its armature so that the valve 44 then closes the slot or wind way 46 and cuts the pneumatic 31 from communication with the interior of 40 the chamber or box 2. When the valve 44 is moved away from its seat through the agency of said electromagnet 41, it puts the pneumatic 31 into communication with the atmosphere, the pneumatic exhausting to the interior of the body 35 and from the latter to the tube 36, which in turn connects with the ports 24 and 23 and port or wind way 22 to atmosphere. When this particular condition does ensue, due in the present case to the 45 energization of the electromagnet 41, the valve 29 will be operated, owing to the collapse of the pneumatic 31, so that the bellows 4 is put into communication with the atmosphere in the manner I have already set forth.

The electromagnet 41 may be energized from any appropriate mechanism. For instance, from the battery 49, one terminal of which is connected by a wire as 50 with one 50 terminal of the magnet, the other terminal of the magnet being connected by wires 51

and 52 through the cable 53 back to the battery by way of wire 54 which as I will now explain is connected to the battery through a suitable switch. This wire 54 leads to the 65 terminal 55 with which the switch 56 is connected. Said switch, shown conventionally, ordinarily consists of a key. Complemental to the contact 55 is the contact 57 connected by wire 58 to the terminal of the battery 49 70 opposite that from which the wire 50 leads. In Fig. 1 the switch is shown as open. To close the switch it is moved against the contact 57.

I have mentioned the fact that certain of 75 the parts may be die cast. Such parts may be made from any suitable material such as vulcanite or papier-mâché which are merely two of several illustrations. When of vulcanite or papier-mâché I would probably 80 mold such parts.

What I claim is:

1. A valve mechanism for use in an electropneumatic organ action, comprising two sections exact duplicates of and connected 85 with each other to constitute a closed box, each section having openings constituting ports, means permanently closing a port of one of the sections, a valve enclosed by the valve mechanism, and means for causing the 90 valve to open and close ports on the two sections alternately.

2. A valve mechanism for use in an electropneumatic organ action, comprising two metal die cast sections exact duplicates of 95 and connected with each other to constitute a closed box, each section having openings constituting ports, means permanently closing a port of one of the sections, a valve enclosed by the valve mechanism, and means 100 for causing the valve to open and close ports on the two sections alternately.

3. An electropneumatic organ action including a valve mechanism comprising two sections exact duplicates of and connected 105 with each other to constitute a closed box, each section having openings constituting ports, means permanently closing a port of one of the sections, a valve enclosed by the valve mechanism, means for causing the 110 valve to open and close ports on the two sections alternately, said means comprising a pneumatic for operating said valve, and a magnet mechanism for operating said pneumatic.

In testimony whereof I affix my signature in the presence of two witnesses.

BASIL G. AUSTIN.
